UNITED STATES PATENT OFFICE.

EDWARD ARMSTRONG BELLOW, OF CODSALL, ENGLAND, ASSIGNOR OF ONE-HALF TO KYNOCHE, LIMITED, OF WITTON, BIRMINGHAM, ENGLAND, A COMPANY OF GREAT BRITAIN.

HINGE.

1,312,944.

Specification of Letters Patent.

Patented Aug. 12, 1919.

Application filed February 25, 1919. Serial No. 279,164.

To all whom it may concern:

Be it known that I, EDWARD ARMSTRONG BELLOW, a subject of the Kingdom of Great Britain, residing at High Elms, Codsall, in 5 the county of Stafford, England, ironmonger, have invented certain new and useful Improvements in Hinges, of which the following is a specification.

This invention relates to hinges of the 10 type which are particularly applicable to out-door work, the improvements comprising a form of hinge entirely of wire, and which is particularly adapted to obviate any rusting up or binding from weather effects. 15 In order that this invention may be clearly understood and readily carried into practice, reference may be had to the appended explanatory sheet of drawings, upon which:—

Figure 1 illustrates in elevation a hinge 20 constructed according to the present invention.

Fig. 2 illustrates in plan the hinge shown in Fig. 1, and indicates its position in relation to two relatively hinged parts.

25 In a convenient embodiment of this invention, the one part of the hinge is shaped substantially to the form of a wire staple *a*, the sides *b* of the staple being advantageously slightly inclined toward each other 30 and curled at their ends to form eyes *c* for receiving the fixing screws. The transverse part of the staple is adapted to form the pivot of the hinge. The other part of the hinge is also shaped to the form of a wire 35 staple having the ends of its side parts *d* bent to form eyes *e* for the fixing screws, the side parts of the staple being curled or bent around the transverse part of the other element *a* of the hinge, such bending over 40 or curling being effected until the transverse part *f* is in proximity to the plane containing the side parts *d* of the staple forming this second part of the hinge.

It will be observed upon reference to 45 Fig. 1 of the drawings, that the arms *d* of

one hinge section or member are parallel and that the arms *b* of the other section or member converge outwardly. This arranges the eyes *c* at approximately the same distance apart as the eyes *e* so that the hinge 50 can be reversed and the eyes of either member caused to register with the same pair of screw holes. The members being made of wire, the arms *d* may be readily moved or sprung toward each other at their outer 55 ends, to cause the space between the eyes *c* to exactly equal the space between the eyes *e*.

As shown in Fig. 2, the arms *b* are slightly bent outwardly from the main plane of the hinge section in order that the pivot *a* may 60 be encircled by the arms *d* when the hinge sections are co-planar.

The wire from which the hinges are formed is advantageously of circular cross-section, but the eyes and bearing parts of 65 the hinge may if desired be flattened in a press so as to have a flat bearing against the surface to which the hinge is fixed, and at the same time reduce the amount of the projection of the hinge.

70 What I claim as my invention and desire to secure by Letters Patent is:—

A hinge comprising a pair of substantially U-shaped sections, each made of a single piece of wire, the eight portions of said 75 sections being pivotally connected together and the arms of said sections having eyes at their outer ends, the arms of one section being parallel and the arms of the other section converging outwardly so that the 80 space between the eyes of one section is approximately equal to the space between the eyes of the other section.

In witness whereof I have hereunto set my hand in the presence of two witnesses.

EDWARD ARMSTRONG BELLOW.

Witnesses:

ARTHUR H. BROWN,
EDGAR N. WHEELER.
